UNITED STATES PATENT OFFICE.

HARRY PFANNENSTIEHL, OF ANTWERP, BELGIUM, AND ARTHUR HERMAN ADAMS, OF SPARKILL, NEW YORK, ASSIGNORS TO WESTERN ELECTRIC COMPANY, OF NEW YORK, N. Y., A CORPORATION OF ILLINOIS.

IMPULSE-PRODUCING MECHANISM.

1,158,951.

Specification of Letters Patent.

Patented Nov. 2, 1915.

Application filed August 19, 1914. Serial No. 857,493.

To all whom it may concern:

Be it known that we, HARRY PFANNENSTIEHL and ARTHUR HERMAN ADAMS, citizens of the United States of America, residing at 112 Rue van Schoonbeke, Antwerp, Belgium, and Sparkill, Rockland county, State of New York, United States of America, respectively, have invented certain new and useful Improvements in Impulse-Producing Mechanisms, of which the following is a full, clear, concise, and exact description.

This invention relates to impulse producing mechanisms particularly as adapted for use in automatic telephone exchange systems being of the type known as "dial senders" or "fingerwheels." That is to say, the invention relates to an impulse mechanism located at the subscriber's station by which he controls the operation of the automatic selector switches at the central or switching station.

One of the objects of the invention is to produce a reliable and simple impulse producing mechanism of small compass and positive operation.

A particular feature of the invention, therefore, whereby an impulse mechanism of the type referred to may be made of compact compass containing all the essential elements thereof without sacrificing either the efficiency or the durability thereof, involves such an arrangement that the governor by which the impulse producing part is controlled in its impulse producing movement is carried by and moves with such part.

Another feature directed to the same end involves an arrangement whereby the governor lies in part above the plane of the finger disk by which the impulse producing part is adapted to be manually set before the initiation of its impulse producing movement. By means of this feature the usual rotating parts of a device of this character may be associated with one another in a very compact arrangement, the governor being so arranged with relation thereto that it projects beyond the plane of such rotating parts without interfering in any way with its operation and function, at the same time permitting the entire structure to be of the smallest possible compass consistent

with number, structure and essential interrelation of the parts to be inclosed.

55

Another feature relates to the arrangement of the teeth or projections on the impulse producing part or wheel of a device of the character referred to, such an arrangement providing that the teeth are located on a periphery of said wheel, and coöperate with a lever for operating the impulse contacts to move such lever to affect such contacts only when such impulse producing part or wheel is moving in a given direction.

60

Another feature relating specifically to devices of this character in which the number plate carrying the numbers by which the openings on the finger disk may be identified, is a separate element from such finger disk, and involves such an arrangement of the device that said finger disk and number plate move together, the number plate being located behind the finger disk so that during the movement of the finger disk in the impulse producing movement of the device the numbers upon the number plate are not readily distinguishable through the openings of said finger disk. Due to this arrangement of the number plate and the finger disk the user will not attempt to actuate the finger disk during the return movement thereof.

70

Still another feature relating specifically to devices of this type in which the setting movement of the finger disk is against the tension of a spring in such a manner that power is stored up in such spring to return the impulse producing parts to normal from a set position, involves that such spring is located in a tubular stud upon which stud certain of the rotatable parts of the device are mounted.

80

Other features of the invention relate to the manner in which the governor is carried by the finger disk, the relation of the governor to the other parts of the device, the manner in which the various parts are inclosed, and details of the driving mechanism for said governor, which features however will sufficiently appear from a description of the embodiment of the invention as hereinafter set forth.

90

In the drawings in which similar reference characters indicate the same parts in

100

105

the different figures thereof: Figure 1 is a front view of an impulse mechanism embodying the invention with the cover removed and certain parts broken away in order to show more clearly certain interior arrangements thereof, Fig. 2 is a section on lines 2—2 of Fig. 1, Fig. 3 is a front view of the device with the fingerhole disk, governor and certain other parts removed, Fig. 4 shows the star-wheel, impulse lever and contact springs, for clearness the star-wheel being shown detached from its supporting parts, Fig. 5 is a front view of the complete device, Fig. 6 is a detail of the rotatable governor carrying part, Fig. 7 is a section on the line 7—7 of Fig. 6, Fig. 8 shows the impulse lever.

In these figures 10 represents the outer casing to which is fastened the plate 11 carrying the contact spring 12 and the contact member 13 together with the pivotally mounted impulse lever 14. Spring 15 holds such lever 14 in the position shown in Fig. 4, the free end of such spring resting in a groove formed on the under side of such lever. The plate 11 is fastened to the casing 10 in any desired manner, such as by screws passing through the holes 16—16. Also mounted upon and fastened to the plate 11 by the rivets 17—17 is the tubular mounting shaft or stud 18 having a shouldered portion 19 and a threaded portion 20.

A circular dished plate 21 is adapted to be mounted upon said stud and fit around the shouldered portion 19 thereof. Riveted to this plate on the rear thereof is the star-wheel 22 provided with teeth adapted to cooperate with the impulse lever 14 as such star-wheel rotates. As shown, the teeth 23 comprise nine small teeth 23 and one longer tooth 24. Mounted on the flat forward annular portion of the plate 21 and fastened thereto by means of screws adapted to enter the holes 25, is a frame casting 26 adapted to carry the governor 27 and the pinion 28 and upon which is also mounted the worm-wheel 30 cooperating with said governor. On the front of the frame 26 and extending laterally beyond such part is the arcuate piece 31 in which are formed the finger-holes by which the device is operated by the telephone user. Part 31 is fastened to the frame 26 by means of screws 32.

A ratchet wheel 33 is screwed down upon the threaded portion of the mounting stud 18. By means of the shoulder 19 the ratchet wheel 33 will be prevented from exerting any binding pressure upon the plate 21. The ratchet wheel 33 has a forwardly extending tubular portion upon which is mounted in close association, but not fastened thereto, a dished gear wheel 34. The thickness of the gear wheel 34 as mounted upon the tubular portion of the ratchet wheel 33 is such that the nut 35 also adapt-

ed to be screwed down upon the threaded portion of the stud 18, will firmly fasten the ratchet wheel 33 to such stud without coming in contact with the gear wheel 34 so that this gear wheel is loosely mounted upon the tubular portion of the ratchet wheel 33. The gear wheel 34, however, has mounted upon the rear thereof a pawl 36 adapted to coöperate with the teeth of the ratchet wheel 33 in such a manner that although the gear wheel 34 may be rotated in a clockwise direction, the engagement of the pawl 36 with a tooth of the ratchet wheel 33 will positively prevent the rotation of such gear wheel in a counter-clockwise direction.

Inside the tubular stud 18 is located a spring supporting rod 37 to the inner end of which is riveted a winged plate 38 which is adapted to fit in an opening 39 in the plate 11 and against a cut-away portion of the base of said stud 18.

Mounted on the rod 37 is the coiled spring 40. This spring is fastened at its inner end to the plate 38 and at its outer end is adapted to be fastened to a centrally extending hub portion 41 of the frame 26 in a manner to be hereinafter described. The frame 26 (shown more clearly in Figs. 6 and 7) is formed of a generally annular portion with an outwardly extending part 42 and an inwardly extending hub part 41. Between an arm 43 of the part 26 and the dished plate 21 is adapted to be carried the pinion 28. Coöperating with the worm-wheel 30 of such pinion and carried between the part 42 and the shoulder 44 on the annular portion of the part 26, is the governor 27. This governor is of ordinary construction and need not be described in detail.

Fastened between the forwardly extending periphery of the plate 21 and the frame 26 is the number plate 48. This plate, as will be noted from Fig. 2, lies behind the finger-hole part 31 and the numbers indicated thereon stand behind the respective holes in such part 31.

Fastened to the base plate 11 and extending through the side of the casing is the finger stop 49. Also fastened to and insulated from the plate 11 are the usual conductor terminals 50 and 51. The contact spring 12 and contact member 13 are also insulated from the base plate.

The circuit may be arranged in any manner desired, provided, of course, that such circuit leads through the contact parts 12 and 13 which are to be operated by the lever 14 in the operation of the device. As shown the ends of the terminals 50, 51 extend over a cut-away portion of the plate 11 through which the external conductors may be led to and fastened to the terminals.

A cover 52 is provided adapted to be fastened to the front of the frame 26 by means of screws so that the interior mechanism of

the device may be properly protected. This cover may have upon the face thereof any necessary instructions to the telephone user, relating to the operation of the device.

5 In assembling the impulse mechanism shown herein the tubular mounting stud 18 and contact members and terminals are first secured to the plate 11. The dished plate 21 to which the star wheel 22 is attached is then placed in position on the mounting stud. The ratchet wheel 33 is then securely screwed down upon the threaded portion of the mounting stud and the gear wheel 34 placed in position on the tubular hub portion of said ratchet wheel, the hole 53 in said gear wheel being provided to assist in properly locating the pawl 36 in connection with the teeth of the ratchet wheel 33. These parts being in position the nut 35 is screwed down firmly upon the tubular mounting stud to hold the ratchet wheel 33 in fixed position with relation to the tubular mounting stud 18. The dished plate 21 carrying the star wheel 22 is free, however, to rotate in either direction upon such mounting stud and the gear wheel 34 is free to rotate in a clockwise direction upon such stud being only prevented from rotating in a counter-clockwise direction by the pawl 36 25 coöperating with the ratchet wheel 33. The rod 37 and winged plate 38 carrying the spring 40 is placed in position in the tubular mounting stud 18, and the frame 26 with the governor 27 mounted thereon, in a manner readily to be observed from the drawings, is fitted in position on the dished plate 21 with the number plate 48 between them and the pinion 28 placed in its bearings in the frame 26 and the plate 21. The frame 26 is firmly screwed to the plate 21 by means of the screws 32 which also serve to hold the number plate in proper position. In locating the frame 26 the hub portion 41 thereof has been fitted upon the top of the tubular mounting stud 18 and the extension 54 of the spring drawn therethrough. These parts having been assembled in the manner described the casing 10 with the stop 49 extending through an opening in the side 45 thereof is placed over the rear of these parts and the base portion is firmly fastened to the plate 11 by means of screws entering the openings 16 therein. The stop 49 is also screwed to the plate 11 by screws passing through the portion thereof inside the casing, such screws being accessible through an opening in the back of the casing. The projecting lug 55' on the frame 26 is placed adjacent to the inward extension 56 of the 50 stop member and the extension 54 of the spring is turned in a clockwise direction until the proper tension is given to the spring 40 and such extension is then snapped into one of the slots 55 to maintain the 55 spring under the tension established. Owing

to the tension given the spring 40 the winged plate 38 has been rotated slightly to clamp itself in the manner of a bayonet joint in the undercut portion of the base of the stud 18 so that the rod 37 is now fastened in position with the spring under proper tension. Finally the cover 52 is placed in position and screwed down upon the frame 26.

The impulse mechanism as shown herein while it is adapted for many uses in connection with telephone systems of widely varying character is particularly designed for systems in which the respective series of controlling impulses are formed of circuit interruptions varying in number according to 75 the particular digit which it is desired to send, each of such series of interruptions being made up of one long impulse (the last one sent) and if more than one impulse is to be sent, of the necessary number of short 80 impulses preceding such long impulse. Furthermore, in the particular type of systems in which it is desired to use the mechanism herein disclosed the number of impulses 85 actually produced in the circuit is the complement of the digit to be sent and in accordance with which the device is operated. That is to say—to send the digit 9, one impulse (the long one) is produced in the circuit: To send the digit 8, two impulses—a 90 short one and then the long one: To send the digit 7, three impulses—two short impulses followed by the one long impulse: To send the digit 1, nine impulses—that is eight short 95 impulses followed by the one long impulse, and to send the digit 0, ten impulses—that is nine short impulses followed by the one 100 long impulse.

Assuming that the telephone user desires to send the digit 1, which it is noted should 105 produce in the circuit eight short impulses followed by the long impulse, he will insert his finger in the hole of the plate 31 which rests before the number 1 upon the number plate 48 and turn such plate 31 in a clockwise direction until his finger comes in contact with stop 49. In doing this he has turned with the plate 31 the frame 26, the number plate 48, the dished plate 21 and the star wheel 22. In this clockwise movement 110 of the star wheel 22, the teeth 24 and 23 as they pass and move the impulse lever 14 have caused such movement of the lever 14 without causing the lever to effect in any way the contact members 12 and 13. This 115 will be readily remarked from an examination of Fig. 4. As the tooth 24 pushes up the long arm of the lever 14 the contact operating portion of such lever will be moved away from the spring 12 and have no effect 120 thereon. The clockwise movement of the parts therefore has had no effect upon the circuit and no impulses have been produced therein by such movement. It should be 125 further noted that this movement is not 130

controlled by the governor 27 for the reason that the gear wheel 34, being free to move in a clockwise direction, has moved with the frame 26 and the pinion 28 and consequently 5 the governor has not been operated.

In the clockwise movement of the finger-hole plate 31 the movement of the hub portion 41 of the frame 26 with such finger-hole plate has caused the spring 40 to be placed 10 under further tension to restore the frame 26, plate 21 and star wheel 22 to their normal position when the plate 31 is released by the telephone user. When this release takes place the tension exerted by the spring 15 40 causes the parts 31, 26, 21 and 22 to be restored to their normal position by a movement in a counter-clockwise direction. In this movement the gear wheel 34 being held stationary by the pawl 36, the pinion 28 20 which engages such wheel and which is now being carried around such gear wheel in a counter-clockwise direction by the frame 26, operates the governor 27 in the well-known manner to check to the necessary extent 25 the speed of this counter-clockwise movement of the parts.

In the assumed clockwise movement of the star wheel 22 the long tooth 24 and eight of the short teeth 23 have been moved past 30 the impulse lever 14. Therefore in the counter-clockwise movement eight short teeth 23 will be moved past the lever 14 and then the long tooth 24. As each tooth in this counter-clockwise movement passes the 35 lever 14, it depresses the long arm of such lever thereby causing the contact arm thereof to come in contact with the contact spring 12 and move it out of engagement with the contact member 13 opening the 40 circuit between such spring and such member. The duration of the interruption of the circuit depends upon the rate of movement and the angular width of the teeth. The rate of movement being maintained 45 relatively constant by the governor. Eight short impulses, or interruptions, will be produced in the circuit by the eight teeth 23 as they pass by the impulse lever 14, such eight short impulses being followed by one 50 long impulse or interruption, of the circuit, produced by the longer depression of the long arm of the impulse lever 14 by the long tooth 24. After the completion of the long impulse the moving parts coming into normal 55 position will be positively stopped in such position by the engagement of the lug 55 with the extension 56 upon the stop member. To send any other digit a corresponding operation will take place, the proper number 60 of impulses being sent for each digit, the last impulse always being the longer one produced by the tooth 24.

It will be obvious that if desired the impulses produced might be closures of the 65 circuit, instead of being interruptions of

the circuit, merely by a re-arrangement of the contact members 12 and 13. It will be further obvious that other changes may be made in the structure of the device as possibly should be found necessary for a particular installation without departing from the invention, such for example as substituting a short impulse for the long impulse referred to, as reversing the numbers on the number plate and so forth. 70

We claim:

1. In an impulse mechanism, the combination with a pair of contacts, a manually movable part comprising means for actuating said contacts, a governor operatively associated with said part to control its speed during its impulse producing movement, said governor being carried by and moving with said part. 80

2. In an impulse mechanism, the combination with a pair of contacts, a manually movable part comprising means for actuating said contacts, a governor operatively associated with said part to control its speed during its impulse producing movement, 90 said governor being carried in a recessed portion of said part. 85

3. In an impulse mechanism, the combination with a pair of contacts, of a manually movable part comprising means for actuating said contacts, a finger disk, and a governor for controlling the impulse producing movement of said part, said governor being carried by said part, and lying in part above the plane of said finger disk. 95 100

4. In an impulse mechanism, the combination with a pair of contacts, of a toothed wheel for actuating said contacts, a finger disk for setting said wheel and a governor for controlling the speed of movement of said wheel, a common support for said finger wheel and governor arranged to move with said wheel, and a shaft upon which said support and wheel rotate. 105

5. In an impulse mechanism, the combination with a pair of contacts, of a part adapted to control the same comprising a finger disk and a governor, a common support for said governor and finger disk, said support being recessed to carry said governor and also provided with a centrally extending portion, and a shaft extending through an opening in said portion and about which said support rotates. 110 115

6. In an impulse mechanism, the combination with a pair of contacts, of a manually movable part adapted to control the same and having a finger disk by means of which it is set, a motor for restoring said part, and a governor controlling the speed of said restoring movement, said governor being located in part above the plane of said finger disk. 120 125

7. In an impulse mechanism, the combination with a pair of contacts, a manually 130

- movable part adapted to control the same comprising in part a finger disk having an opening for each digit and a number plate behind such finger disk, a spring for restoring said part, said finger disk and number plate being adapted to move together in both directions.
8. In an impulse mechanism, the combination with a pair of contacts, of a movable spring-restored part comprising a finger disk, a plate, a toothed wheel and a cover plate, said toothed wheel being adapted to actuate said contacts, said plate and cover plate being shaped to form together a chamber, and a governor controlling the restoring movement of said part and located in said chamber.
9. In an impulse mechanism, the combination with a pair of contacts, of a spring-restored supporting plate, a pair of concave plates and a finger disk attached thereto, a toothed wheel mounted upon the rear one of said plates and adapted to actuate said contacts, said plates forming an enlarged chamber centrally of said finger disk, and a governor mounted upon said support within said chamber, and adapted to control the speed of said toothed wheel.
10. In an impulse mechanism, the combination with a pair of contacts, of a spring-restored supporting plate, a pair of concave plates and a finger disk attached thereto, a toothed wheel mounted upon the rear one of said plates and adapted to actuate said contacts, said plates forming an enlarged chamber centrally of said finger disk, a governor mounted upon said support within said chamber and controlling the speed of said supporting plate, a stud, said supporting plate having a centrally extending projection provided with an opening through which said stud projects, and the rear plate being also provided with an opening forming the other bearing for the moving parts.
11. In an impulse mechanism, the combination with a pair of contacts, of a part adapted to be rotated by hand and in its restoring movement to control said contacts, said part being mounted to rotate upon a hollow stud, a spring for restoring said part, a base plate, and a plate to which said spring is attached, said plate being secured to said stud by a bayonet joint between an undercut portion of said stud and the base plate, and the other end of said spring being secured to the said rotating part.
12. In an impulse mechanism, the combination with a pair of contacts, a spring-restored movable part adapted to control said contacts, a governor movable with said part and adapted to control the restoring movement thereof, and a gear wheel movable with said part in its setting movement but being restrained from moving during the return movement, said governor in such return movement being operatively connected to said gear and being thus driven thereby.
13. In an impulse mechanism, the combination with a pair of contacts, a spring-restored movable part adapted to control said contacts, a governor movable with said part and adapted to control the restoring movement thereof, a fixed ratchet wheel, and a gear wheel movable with said part during its setting movement and carrying a pawl adapted to engage said ratchet wheel during the return movement of said part, said governor in such return movement being driven by said gear wheel.
14. In an impulse mechanism, the combination with a back plate, a pair of contacts and a lever for actuating the same mounted thereon, a fixed ratchet wheel, a manually movable part comprising a finger disk, an impulse wheel for operating said lever, a governor for said wheel, a gear wheel, and a pawl carried by said gear wheel and riding loosely over the teeth of said ratchet wheel during the setting of said finger disk but engaging said teeth and being held rigid during the return movement, said governor being operatively connected to and driven by said gear wheel in such restoring movement to control the speed of said impulse wheel.

In witness whereof, I hereunto subscribe my name this 28th day of July A. D. 1914.
